CATHEAD FOR DRILLING RIGS

Ira T. Minyard, Odessa, Tex.

Application July 25, 1940, Serial No. 347,515

2 Claims. (Cl. 254—185)

This invention relates to a cathead for drilling rigs.

It is particularly aimed to provide a novel construction wherein two or more spools or drums may be operated on the same shaft, independently of each other, in order to work two separate cat lines.

It is particularly aimed to provide such a structure as forms an attachment for drilling rigs, including a means attachable to the rotary shaft of the latter and which accommodates the cathead normally attached to such shaft.

The invention generally adds to the safety to operators since the wrapping of a rope around the conventional type of cathead and lifting articles in the rig is extremely dangerous. The improvement renders it unnecessary to wrap the line around a spool since the steel line is fastened on one of the spools and upon being wound, lifts the load which is attached to the other end of the line. There are of course various other operations in oil well drilling which require the use of a cat line and with the present invention, such jobs can be performed with greater safety, speed and more economically.

Various additional objects and advantages will become apparent from a consideration of the description following taken in connection with accompanying drawings, illustrating an operative embodiment.

In said drawings:

Figure 1 is a side elevation of the construction;

Figure 2 is a vertical sectional view taken on the plane of line 2—2 of Figure 1;

Figure 3 is a central longitudinal section taken on the plane of line 3—3 of Figure 1;

Figure 4 is a cross section taken on the line 4—4 of Figure 3;

Figure 5 is a detail section illustrating one of the hydraulic devices for operating the yoke of the spinning line drum, and

Figure 6 is a detail section of one of the hydraulic devices for operating the yoke of the derrick line drum.

Referring specifically to the drawings wherein like reference characters designate like or similar parts, 10 represents the rotary shaft of a drilling rig and 11 indicates a cathead of conventional construction and which is usually removably keyed to the shaft 10. In accordance with the present invention, a supplemental shaft is provided at 12 having one end portion 13 formed into a sleeve which receives and at 14 is keyed to that end of shaft 10 on which the cathead 11 of usual construction is carried. 55

Auxiliary shaft 12 is held against axial displacement by means of a rod 15 screwed at 16 to a fixed nut or the like 17 fastened to the adjacent end of shaft 10. A disk 18 overlaps the free end of auxiliary shaft 12, and a key 19 which engages the cathead 11 and rod 15 passes through disk 18 and beyond the same receives a fastening nut or the like 20.

Loosely and slidably mounted on a portion 21 of auxiliary shaft 12, of reduced diameter, is a spinning line spool or drum 22, the spinning line of which is shown at 23. Roller bearings at 24 are operatively disposed between the drum 22 and shaft portion 21. Drum 22 has a cone clutch flange or section 25, normally disengaged from but engageable with a cone clutch section or head 26 provided on the cathead 11 and which is preferably lined as at 27.

The spinning line 23 is accommodated between the section 25 and a flange 28 and between the latter and a flange 29, a shifting yoke 30 is mounted for axial movement in either direction, the yoke having rollers 31 engageable with either flange 28 or 29. Such yoke 30 is preferably made in two sections having outwardly extending arms 32 bolted together at 33 as best shown in Figure 2.

On a portion 34 of auxiliary shaft 12, a derrick line drum or spool 35 is loosely and slidably mounted, with roller bearings 36 operatively disposed between the drum and said enlarged portion. The derrick line is shown at 37 and accommodated between a head or section 38 thereon and a flange 39. Section 38 interiorly is conical and normally disengaged from but movable to engage a clutch head or section 39', of conical form, preferably lined as at 40.

The periphery of section 38 constitutes a braking surface and it is surrounded by a contractile brake band 41, normally disengaged therewith. Movable in opposite directions between flange 39 and a flange 41 on the drum 35, is a yoke 42 constructed similarly to the yoke 30 and having connected outwardly extending arms 43 similar to those at 32, the connecting bolts or the like being indicated at 44. Yoke 42, has rollers 45 mounted thereon for engagement with either flange 39 or 41.

Hydraulic cylinders 46 and 47 are mounted in any suitable manner on the exterior of a generally cylindrical casing or housing 48 provided about the operating parts and being adapted for attachment at one end to a stationary part of the drilling rig and for instance at a flange 49 by means of bolts passed through openings 50.

Slidable in the cylinders 46 and 47 are pistons 48' and 49', respectively, having rods 50' and 51 extending through end walls thereof and connected to the arms 32 and 43. Surrounding the rods 50' and 51, are coil springs 52 and 53, respectively, which maintain and urge the pistons 48' and 49' to positions in which the associated yokes 30 and 42 maintain the drums 22 and 35, loose and unclutched. Such cylinders 46 and 47, and pistons 48' and 49' therein are under control of pressure lines from master cylinders, the pressure lines being shown connected as at 54 and 55 to the respective cylinders. It will be noted that the arms 32 and 43, extend through enlarged openings 56 and 57 of the casing 48.

Reverting to the brake band 41, it is anchored at one end as by means of a pin 58 to the casing 48 and its other end is fastened as by means of a pin 59 to a manually operable lever 60 pivoted as at 61 to the casing 48.

The spinning line 23 passes out through a suitable opening 62 in casing 48, its inner end being fastened to the drum 22. The derrick line 31 passes out from the casing through an elongated slot 63, and its inner end is fastened to the drum 35.

It will be realized that the drum will allow the shaft 10 and auxiliary shaft 12 to continue to revolve after the drums 22 and 35 have spooled up the desired amount of line.

Various changes may be resorted to provided they fall within the spirit and scope of the invention.

I claim as my invention:

1. A cathead construction of the class described having a rotatable shaft, a clutch head rigid thereon, a cathead rigid thereon having a clutch head, a spinning line drum loose and slideable on said shaft to engage and disengage one of said heads, a derrick line drum loose and slideable on said shaft to engage and disengage the other of said heads, a casing surrounding said heads and drums, means operable to slide the drums mounted on the exterior of said casing, comprising yokes disposed about the drums, hydraulic cylinder and piston devices, and connections from the yokes extending through the casing and connected to the piston devices.

2. A cathead construction of the class described having a rotatable shaft, a clutch head rigid thereon, a cathead rigid thereon having a clutch head, a spinning line drum loose and slideable on said shaft to engage and disengage one of said heads, a derrick line drum loose and slideable on said shaft to engage and disengage the other of said heads, a casing surrounding said heads and drums, means operable to slide the drums mounted on the exterior of said casing, comprising yokes disposed about the drums, hydraulic cylinder and piston devices, connections from the yokes extending through the casing and connected to the piston devices, and rollers on said yokes, said drums having flanges between which the rollers are disposed and which are engageable by the rollers.

IRVING T. MINYARD.
